CLAIM

The ornamental design for a container for fluids, as shown and described.

DESCRIPTION

1.1 is a side elevation view of a container for fluids.
1.2 is a rear elevation view of the container of FIG. 1.1.
1.3 is a front elevation view of the container of FIG. 1.1.
1.4 is a front and side perspective view of the container of FIG. 1.1.
2.1 is a side elevation view of a container for fluids.
2.2 is a rear elevation view of the container of FIG. 2.1.
2.3 is a front elevation view of the container of FIG. 2.1.
2.4 is a front and side perspective view of the container of FIG. 2.1.

(Continued)

The broken lines shown in the drawing represent unclaimed portions of the container for fluids and form no part of the claimed design.
